C. F. PAUL, JR.
CONNECTOR FOR ELECTRICAL TERMINALS.
APPLICATION FILED SEPT. 20, 1912.

1,222,022.

Patented Apr. 10, 1917.

UNITED STATES PATENT OFFICE.

CHRISTIAN F. PAUL, JR., OF PEEKSKILL, NEW YORK, ASSIGNEE OF ONE-HALF TO
CYRIL G. BALLIN, OF NEW YORK, N. Y.

CONNECTOR FOR ELECTRICAL TERMINALS.

1,222,022.

Specification of Letters Patent. Patented Apr. 10, 1917.

Application filed September 20, 1912. Serial No. 721,364.

To all whom it may concern:

Be it known that I, CHRISTIAN F. PAUL, Jr., a citizen of the United States, residing at Peekskill, New York, have invented certain new and useful Improvements in Connectors for Electrical Terminals, of which the following is a clear, full, and exact description.

This invention relates to an electrical connector for coupling together the terminals of conductors of electrical machines, and is particularly applicable to those machines subject to rough usage and considerable vibration, such as the motor-driven rock drills, 15 electrically operated hammers, etc.

In general my connector comprises two separate holders, each carrying one or more terminals for coming into contact to complete an electrical circuit. One holder is 20 adapted to be secured to the rigid base of the electrical machine, and the other holder is manually portable and removable from said first named holder for breaking the electrical connections.

25 In the use of rock drills the means for making the electrical connections to the motor of the drill soon become clogged up with dirt and grit and should therefore be open and exposed to facilitate cleaning. Also the 30 method usually adopted by workmen for insuring good electrical contact between the connections is to drive the parts together with a heavy rock or sledge hammer. It is therefore desirable that the parts which 35 carry the terminals for making the electrical connections be designed to protect the terminals against injury when subjected to such rough usage.

The present improvement secures the advantages thus found desirable and further 40 advantages of the construction will become apparent from the following description and accompanying drawings. The scope of the invention will be pointed out in the appended claims.

45 In the preferred embodiment of the invention illustrated in the drawings,

Figure 1 is a front elevation of the connector showing the cover-plate of the head and the retaining nuts 28 removed;

Fig. 2 is a cross-section taken on the line II—II of Fig. 1; and

Fig. 3 is a cross-section taken on the line III—III of Fig. 1 but showing the connec-

tor head as being only partly slid into its 55 normal position.

Referring more particularly to the drawings, 1 represents the outline of the shell of a motor to which the connector is to be applied. To hold the conductors 2 which lead 60 to the interior of the motor, I provide an insulating block 3 which is clamped on the exterior of the shell 1 by means of a base plate or holder 4. The conductors 2 are secured in the inner ends of fixed terminals 65 5 which pass through this fixed insulating block. These fixed terminals may be molded in the insulator 3 and may have enlargements 6 to prevent their displacement. The outer ends of the terminals 5 are slightly 70 cupped so as to form circular sockets 7 with beveled walls.

At the opposed sides of the fixed holder 4 are formed grooved portions 8 for guiding tongues 9 formed at the lateral edges of the 75 portable holder 10, said holder being in the form of a plate, having a rounded head 11. The tongues 9 are tapered or wedge-shaped in longitudinal section as shown in Fig. 3 and the grooves 8 are similarly tapered to 80 fit said tongues for allowing the parts to be completely coupled together with a wedging action as shown in Figs. 1 and 2. Although the wedging action of the tapered tongues 9 and grooves 8 is generally sufficient to limit the transverse movement of 85 holder 10 in registering its terminals with those of holder 4, nevertheless I have provided a positive stop or shoulder 35 (see Figs. 1 and 3) for an additional precaution 90 in arresting the movement of said parts in proper relation. The holder 10 has a central opening or bore 12 which communicates with the interior of a tubular shank 13 extending from one side of the holder. In the 95 bore 12 is carried an insulating block, preferably divided in two sections or disks 14 and 15. These disks are formed with sockets 16 for the movable terminals 17. The movable terminals 17 are mounted to slide in a 100 tubular shell formed of two parts 18 and 19, the ends of which come together as shown. The shell members 19 extend through the outer insulating section 15, and to their outer ends conductors 20 are connected. The conductors 20 pass laterally through slots 21 in the outer face of the insulating section 15 and continue through

the tubular shank 13. Within the shell members 18 and 19, springs 22 are provided to force outwardly the reduced tips of the movable terminals 17 so that they tend to 5 project slightly beyond the inner face of the insulating section 14. The outer side of the insulating section 15 is covered by an insulating gasket 23 over which there is received a cover-plate 24 and which fits into an enlarged counterbore 25 in the outer side of 10 the head 11. The shell members 18 and 19 have shoulders 26 which hold them in place when they have been set between the insulating sections 14 and 15. The two sections 14 and 15 are rigidly secured together and simultaneously secured to the holder 10 by means of bolts 27, the heads of which are countersunk in the inner face of the block 14. The outer ends of the bolts pass through 15 the cover-plate 24 and receive nuts 28 and check pins 29. In order to hold these bolts 27 against rotation, cross pins 30 are mounted in openings 31 in the bolts just under the gasket 23, and these pins 30 are received in slots 32 in the outer face of the block 15. Near a shoulder 33 which forms a seat for the gasket 23 an annular internal flange or 20 projection 34 is formed. The block 15 seats against the inner side of this flange, and the gasket 23 and cover 24 seat against the outer side, which is a continuation of the shoulder 33. In this way the bolts clamp the insulating blocks 14 and 15 securely together and at the same time secure them in 25 the holder 10.

Although I have illustrated a connector having three contacts, there may be more or less of the contacts depending upon the nature of the electrical machine or upon the nature of the transmission. In coupling the holder 10 to the base plate or holder 4, it is simply slid along the grooved portions 8 until the coupling movement is arrested by 30 the stop 35 which occurs when the movable terminals are in register with the fixed terminals 5. The springs 22 will then force the projecting ends of the movable terminals 17 into the sockets of the fixed terminals. It will be evident that in spite of vibration or 35 shocks, these springs will maintain a constant contact between the movable terminals and the fixed terminals. It will also be evident that the means for guiding the holder 10 into position is exposed so that any obstructions can be readily removed, and furthermore if it is necessary to use great force in driving the holder into position, this force does not apply itself to the terminals. 40 In other words, the terminals are not driven together but simply slide into engagement with each other.

The terms "vertical" and "horizontal" are used in the claims to indicate directions relative to one another and not in any absolute sense.

It is understood that the construction described above is the preferred embodiment only of my invention which may take many other forms. I therefore do not wish to be limited in the scope of my claims to the particular construction described above. 70

What I claim is:—

1. In a connector for electrical terminals in combination, separate holders having electrical terminals therein, coacting tongue and groove guiding devices upon said holders for guiding said holders one upon the other in a substantially straight path transversely of said terminals for bringing said terminals into register, said tongue and groove guiding devices arranged in converging relation so as to have a wedging action when forced together. 75

2. In a holder for electrical terminals, in combination a casing, a block of insulation therein separable into sections, one or more electrical terminals adapted to be held between said sections when the latter are clamped together, said terminals comprising a two part hollow shell and a plug slidable 80 therein, and means for clamping said sections together. 90

3. In a holder for electrical terminals, in combination a casing, a block of insulation therein separable into sections, one or more electrical terminals adapted to be held between said sections when the latter are clamped together, said terminals comprising a two-part hollow shell and a spring-pressed plug slidable therein, and means for 100 clamping said sections together. 100

4. In a connector for electrical terminals in combination, separate holders each comprising a metallic casing with a body of insulation therein to provide a substantially horizontal face and adapted to slide one upon the other, interlocking portions at the lateral edges of said casings for guiding the holders in their sliding movement one upon the other, one or more electrical terminals 105 mounted in the insulation at the face of each holder and arranged to move vertically toward one another for making contact when said terminals are in register, said terminals being provided with means so that when 110 said terminals come in contact they prevent the relative sliding movement of said holders. 115

5. In a connector for electrical terminals in combination, separate holders each comprising a metallic casing with a body of insulation therein to provide a substantially horizontal face and adapted to slide one upon the other, interlocking portions at the lateral edges of said casings for guiding the holders in their sliding movement one 120 upon the other, one or more electrical terminals mounted in the insulation at the face of each holder and arranged to move vertically toward one another for making contact when said terminals are in register, the 130

5 terminals of one holder having sockets and the terminals of the other holder having projections adapted to enter said sockets so that said terminals when they come in contact act to prevent the relative sliding movement of said holders.

6. In a connector for electrical terminals in combination, separate holders each comprising a metallic casing with a body of insulation therein to provide a substantially horizontal face and adapted to slide one upon the other, interlocking portions at the lateral edges of said casings for guiding the holders in their sliding movement one 10 upon the other, one or more electrical terminals mounted in the insulation at the face of each holder and arranged to move vertically toward one another for making contact when said terminals are in register, the 15 terminals of one holder having beveled sockets and the terminals of the other holder having spring-pressed projections adapted to enter said sockets and yieldingly retain said holders against sliding movement.

20 7. In a connector for electrical terminals in combination, a holder having a central opening with an internal flange, an insulating block within said opening at the inner side of said flange, one or more terminals 25 carried in said block, a cover plate at the outer side of said flange, means for clamping said insulating block and said cover plate together upon said interposed flange, a fixed base, an insulating block held thereon and 30 having one or more terminals therein, said fixed base constructed and arranged to guide said holder in a sliding movement thereon to bring the terminals of said holder into 35 register with the terminals of said base.

40 8. In a connector for electrical terminals in combination, separate holders with opposed faces adapted to slide one upon the other, each holder comprising a protective casing with one or more terminals in the 45 face of the holder and insulated from the casing, inter-locking means at the lateral edges of said holders for guiding the inter-sliding movement thereof in a substantially straight path transversely of said terminals 50 to bring said terminals into register, one of 55 said holders being manually portable and removable from the other holder.

60 9. In a connector for electrical terminals in combination, separate holders with opposed faces adapted to slide one upon the other, each holder comprising a protective casing with one or more terminals in the face of the holder and insulated from the

65 casing, inter-engaging means at the lateral edges of said holders for guiding the inter-sliding movement thereof in a substantially straight path transversely of said terminals to bring said terminals into register, said inter-engaging means comprising coacting tongue and groove portions.

70 10. In a connector for electrical terminals in combination, separate holders with opposed faces adapted to slide one upon the other, each holder comprising a protective casing with one or more terminals in the face 75 of the holder and insulated from the casing, inter-engaging means at the lateral edges of said holders for guiding the intersliding movement thereof in a substantially straight path transversely of said terminals to bring 80 said terminals into register, said inter-engaging means comprising coacting tongue and groove portions arranged to have a wedging action upon one another when the 85 holders are forced together.

90 11. In a connector for electrical terminals in combination, separate holders with opposed faces adapted to slide one upon the other, each holder comprising a protective casing with one or more terminals in the 95 face of the holder and insulated from the casing, inter-locking means at the lateral edges of said holders for guiding the inter-sliding movement thereof in a substantially straight path transversely of said terminals 100 to bring said terminals into register, said terminals having a movement toward one another independent of said holders for making contact.

105 12. In a connector for electrical terminals in combination, separate holders with opposed faces adapted to slide one upon the other, each holder comprising a protective casing with one or more terminals in the face of the holder and insulated from the casing, inter-engaging means at the lateral edges of said holders for guiding the inter-sliding movement thereof in a substantially straight path transversely of said terminals to bring said terminals into register, said 110 terminals having a movement toward one another independent of said holders for making contact, and provided with means when in contact, tending to prevent the intersliding movement of said holders.

Signed at New York, N. Y., this 9th day of September, 1912.
